[57] CLAIM

The ornamental design for a foot hygiene device having a centrally disposed dorsal brush, substantially as shown and described.

DESCRIPTION

FIG. 1 is a top plan view of the foot hygiene having a centrally disposed dorsal brush showing my new design.

FIG. 2 is a bottom plan view thereof.

FIG. 3 is an elevational view of one side thereof.

FIG. 4 is an elevational view of the opposite side thereof.

FIG. 5 is an elevational view of one end thereof.

FIG. 6 is an elevational view of the opposite end thereof.

FIG. 1

FIG. 2

FIG. 3

FIG. 4

FIG. 5
